UNITED STATES PATENT OFFICE.

SAMUEL B. SMITH, OF CLEVELAND, OHIO.

STOVE.

1,189,301.

Specification of Letters Patent. Patented July 4, 1916.

Application filed December 30, 1915. Serial No. 69,323.

To all whom it may concern:

Be it known that I, SAMUEL B. SMITH, a citizen of the United States of America, residing at Cleveland, in the county of 5 Cuyahoga and State of Ohio, have invented certain new and useful Improvements in Stoves; and I hereby declare the following to be a full, clear, and exact description of the invention, such as will enable others 10 skilled in the art to which it pertains to make and use the same.

This invention relates to new and useful improvements in stoves, and especially to a stove known as a brooder stove.

15 The object of this invention is to provide a stove of the character indicated having means for positively controlling the draft so that the heat given off by the stove can be definitely regulated and maintained approximately constant.

A further object is to so construct the stove that it shall be compact as possible having as few attachments as possible and arranging those that are employed in a simple and most convenient way so that it will be free from difficulties due to the use to which the stove is employed. For this reason the base portion is designed to permit the ready application of a horizontal thermostatic arm which projects from the base of the stove close to the floor line and in order to prevent the possibility of the small chicks interfering with the proper operation of the 25 thermostat the movable arm of the thermostatic element is located below the stationary arm and protected by it.

With these objects in view, and with the intention of securing other advantages which will hereinafter appear, my invention consists in the features of construction and combination of parts hereinafter described in the specification, pointed out in the claims and illustrated in the accompanying drawings.

45 In the accompanying drawings, Figure 1 is a top plan of a stove embodying my invention. Fig. 2 is a section on line 2—2, Fig. 1.

Referring to the drawings, it will be seen 50 that my improved stove comprises a hollow base portion 10 in which is arranged a bottom wall 11, and the interior of the base above this bottom wall constitutes the ash-pit, indicated at 12. To the under side of 55 the wall 11 is secured a sheet of suitable heat insulating material 13, preferably as

bestos, and at the under side of the said sheet is preferably arranged a metallic plate 14 which serves to reinforce the insulating sheet and hold it in position. On the base 60 portion 10 is mounted a fire pot section 15, and above the fire pot section 15 is mounted the combustion chamber section 16, the fire pot section and the combustion chamber section being bolted together in the usual manner. In the bottom of the fire pot is mounted the grate which consists of two grate bar sections 17 which are mounted so as to rock. The said grate sections are provided with downwardly extending rigid arms 18 70 which are connected by a link 19 which transmit the motion of one grate bar section to the other grate bar section, so that when either section is rocked the other one will be correspondingly rocked. In the top of 75 the combustion chamber section is formed an opening 21 which is adapted to receive the lower end of a magazine section 22. The magazine section is provided with a removable cover 23 at its upper end to permit of 80 the fuel being supplied thereto. In the top of the combustion section is formed a flue opening 24, and adjacent to the flue opening is formed a check draft opening 25. The check draft opening 25 is provided with a 85 cover 26 which has at one side small trunnions 27 which are mounted in suitable bearings on the top of the combustion section, thereby permitting the cover to swing up and down on the said trunnions. The said 90 cover 26 is provided with an arm 28 which projects outwardly from a point between the trunnions and beyond the edge of the combustion section. On the side of the stove near the base thereof is secured a rigid 95 arm or bracket member 30 which, near its outer end, carries an enlargement or head. 31: Below the rigid arm 30 is arranged a lever 33 which is provided with a head 34 corresponding to the head 31 on the rigid 100 arm. The said lever 33 is fulcrumed or connected at its outer end to the outer end of the rigid arm 30 by means of a screw threaded bolt 35 which passes up loosely through the end of the lever and through the end of 105 the arm 30. On the bolt 35 is arranged a wing nut 36. The opposite end of the lever 33 is connected to the arm 28 on the cover 25 by a link 38. Between the heads on the rigid arm 30 and the lever 33 are arranged 110 a pair of thermostatic elements 37 which are of the usual construction. Within the

combustion chamber on the under side of the top thereof below the flue opening and the draft opening is arranged a check draft chamber 39 which is entirely closed except at one end adjacent to the check draft opening in the top of the combustion chamber.

It will readily be understood that when there is fire in the stove the products of combustion in order to escape will have to enter the check draft chamber, then pass below the check draft opening and escape through the flue-opening. When regulating the stove for maintaining a predetermined temperature the wing nut is so adjusted that there will be the necessary space between the heads on the rigid arm 30 and the lever 33 to accommodate the thermostatic element when expanded for that degree of temperature, and there will therefore be no pressure on the lever. Now, if the temperature rises beyond this predetermined degree the thermostatic elements will expand causing the inner end of the lever to swing down, which will draw down the link 38 connected with the arm 28 on the check draft cover 26 causing the cover to swing up and permitting the outer air to pass into the check draft chamber thereby reducing or counter-acting the draft through the flue. As the stove cools down the temperature will diminish and the thermostatic elements will contract, and when the pressure is removed from the lever 33 the check draft cover will swing down of its own weight.

35 What I claim is:—

1. In a stove, the combination of a base portion, an upper magazine portion having its widest part near the center, the side of same converging from the center, a flat top portion formed by the upper sides, draft and fuel openings located on said flat top and both arranged at one side of the center thereof, a thermostatic device projecting from the base portion, a vertical connecting rod extending upwardly therefrom, a check draft in said draft opening, and means connecting said check draft and said arm, for the purpose specified.

2. In a stove, the combination of a base, 50 a plurality of upper sections formed like

frustums of cones, the two sections being superimposed so that the large portions of the cones are connected together, a reduced flat top portion formed by the converging sides of one section, check draft and fuel 55 openings in said flat top all eccentrically located therein, a rigid thermostatic arm secured to the base, a movable thermostatic element mounted below the arm and protected thereby, a check draft in said draft 60 opening, and means connecting the thermostatic element with said check draft, substantially as specified.

3. In a stove, the combination of a base, 65 an upper section above the base having its widest part near the center of the stove and having its sides converge upwardly, a reduced flat top portion formed by the converging sides, a thermostatic arm projecting horizontally from the base, a vertical 70 connecting rod extending upwardly from said thermostatic arm, check draft and fuel openings located in said flat top portion of the stove and all eccentrically arranged in their relation to said top, a check draft 75 in said draft opening, and means for connecting said check draft to said connecting rod.

4. In a stove, the combination of a base, 80 and a section of stove secured above the base having its sides converge from the center to the top, a reduced flat top portion formed by the converging sides, fuel openings and check draft openings located in the flat top portion, and all eccentrically ar- 85 ranged with the check draft opening located near the outer periphery of the top, a thermostatic arm projecting from the side of the stove, a check draft in said draft opening, and a vertical connecting rod ex- 90 tending between said check draft and said thermostatic arm for the purpose specified.

In testimony whereof, I sign the foregoing specification in the presence of two witnesses.

SAMUEL B. SMITH.
